CARBURETOR

Frank N. Russell, Oakland, Calif.

Application March 13, 1937, Serial No. 130,636

4 Claims. (Cl. 261—78)

This invention relates to carburetors, and has for an object to provide a construction wherein there is provided an improved carburization of the gasoline before it reaches the intake manifold of an engine.

Another object of the invention is to provide a carburetor having a mixing or vaporizing chamber wherein atomized gasoline is discharged.

An additional object of the invention is to provide a carburetor having an atomizing structure for directing a mixture of air and gasoline to an outlet together with auxiliary air supplying means for providing air at different points along the travel of the air and gasoline mixture.

15 In the accompanying drawing:

Fig. 1 is a longitudinal vertical sectional view through a carburetor disclosing an embodiment of the invention;

Fig. 2 is a horizontal sectional view through Fig. 1 approximately on the line 2—2;

Fig. 3 is a transverse sectional view through Fig. 1 on the line 3—3;

Fig. 4 is a transverse sectional view through Fig. 1 on the line 4—4;

25 Fig. 5 is a fragmentary side view showing an accelerator lever and associated parts embodying certain features of the invention;

Fig. 6 is an elevation of one of the valves shown in Fig. 1, the same being on an enlarged scale;

30 Fig. 7 is a fragmentary sectional view through Fig. 6 approximately on the line 7—7.

Referring to the accompanying drawing by numerals, 1 indicates a tubular pipe forming part of the outlet member 2. The tubular outlet 35 tension 1 is adapted to be bolted or otherwise rigidly secured to an intake manifold of an internal combustion engine. If desired, a butterfly throttle valve 3 could be arranged in the tubular member 1 near the outlet end. However, this throttle valve, which is the usual kind now in common 40 use, could be eliminated, but if used it must be connected up to function in synchronism with the valve member 4 hereinafter more fully described.

The tubular outlet 2 is formed as a T-shaped 45 member with the legs 5 and 6 connected respectively to the casing 7 and the pipe 8. Pipe 8 acts as an auxiliary air inlet pipe and is provided with the usual butterfly choke valve 9. Casing 7 with portion 10 of leg 5 forms a vaporizing 50 chamber having a throat or outlet passageway 11 discharging into the tubular outlet 2. An abutment or wall 12 is arranged in line with the center of the tubular outlet 2 and forms a division wall between the vaporizing chamber 10' and the air inlet 8. It will be noted that by reason of

the throats 11 and 11' the vaporized or atomized gasoline and the air both enter the tubular outlet 2 in parallel streams. These streams mix as they pass upwardly to the outlet end of member 1. In case any uncarbureted gasoline passes into the member 1, it is supplied with fresh air from the respective pipes 13 and 14 which are of different heights. These pipes are carried by wall 12 and extend centrally into the tube 1. Wall 2 is provided with a passageway 15 for each of the 10 pipes 13 and 14 so that air passing inwardly through the auxiliary air inlet 8 will strike wall 12 and part of the air will be deflected upwardly and part will pass into the passageways 15 and thence through pipes 13 and 14.

As shown in Fig. 1, there is provided a float chamber 16 which is adapted to carry a supply of gasoline. This float chamber may be of any desired kind and is provided with a float 17 regulating the valve 18 through which gasoline passes from the supply pipe 19. The lid or cover 20 may be secured to the chamber 16 in any desired way and a supporting pipe 21 is secured to lid 12 by nuts 22 and 23. Pipe 21 is screwed into a suitable threaded opening 24 formed in casing 7 so that a plurality of tubes 25 may extend from near the bottom of chamber 16 upwardly into the chamber 10'. These pipes may be held in place by friction or other means and are slightly bent at the upper ends as shown in Figs. 1 and 4. Also it will be observed that the upper ends are at different elevations coacting with the passageways or apertures 26, 27, and 28 formed in the valve casing 29, which casing has a bore for accommodating the valve 4, passageways 30, 31, 35 and 32, as well as the chamber 33. An air inlet pipe 34 continually communicates with the chamber 33 and is supplied with air from a suitable source of compressed air, as for instance a pump or a tank filled with compressed air. From this 40 it will be seen that whenever valve 4 is open fully or partly, air will rush into the chamber 10' and will pass over one or more of the upper ends of tubes 25 whereby gasoline will be drawn up the tubes and discharged with the air into chamber 45 10' in an atomizing manner.

The valve 4, as shown more particularly in Figs. 6 and 7, is provided with passageways 35, 36 and 37 cooperating with the passageways 30, 31 and 32 and the outlet openings 26, 27 and 28. 50 By this arrangement when the valve 4 turns a certain distance, air will pass through passageway 35 and blow across the top of the lowermost tube 25 so as to provide a certain volume of vaporized or atomized gasoline. If the valve 4 is 55

turned a further distance, air will pass through the passageways 35 and 36 so that gasoline will be fed from the second highest tube 25, and if the valve 4 is turned to its full open position, air will pass through all three passageways in the valve so that a maximum atomizing effect is produced and consequently a maximum supply of vaporized gasoline is directed to the tubular outlet 2.

10 Valve 4 is provided with an enlarged end 38 as shown in Fig. 2, which limits the movement of the valve as it is inserted into proper position whereby the various passageways will properly register. An accelerator or throttle lever 39 is 15 secured to the protruding end of valve 4 so as to hold the valve in proper place and also to rotate the valve. This lever may be actuated through link 40 and other mechanism as may be desired. When the throttle valve 3 is used it must be connected with the accelerator lever 39 in some manner so that it will be open as valve 4 opens. However, usually valve 3 is eliminated. A set 20 screw 41 acts to clamp lever 39 rigidly to the valve 4 and also projects outwardly sufficiently far 25 to strike the pipe 34 and limit the opening movement of the lever so that the lever can not be moved further than a full open position for valve 4. An adjustable abutment is also provided for lever 39. This consists of a screw 42 30 locked in place by a suitable lock 2, said screw being threaded into the extension 44 of lever 39.

If desired, the usual spring connected with accelerators may be connected with lever 39, link 40, or any parts associated therewith, so that 35 when the link 40 is released the spring will automatically move lever 39 and associated parts in a direction for closing valve 4. In order to prevent a complete closing of the valve 4 so that the engine may idle, abutment 32 is adjusted and 40 strikes the pipe 34 as shown in Fig. 5. This holds valve 4 sufficiently open to allow idling at any desired speed.

I claim:

1. A carburetor comprising a float chamber, 45 means for directing gasoline into said chamber, a valve for controlling the action of said means, a float for controlling the action of said valve, a plurality of outlet tubes extending from near the bottom of said chamber to a point exteriorly 50 of said chamber, the ends of said tubes exteriorly of said chamber being arranged in different planes, means for directing air under pressure across the tops of said ends for drawing gasoline from said tubes and vaporizing the gasoline at 55 the same time, means forming a mixing chamber for said gasoline and air, an outlet tubular member adapted to lead to the intake manifold of an internal combustion engine, means forming an auxiliary air inlet leading into said outlet 60 tubular member, a baffle between said vaporizing chamber and said air inlet means, and a plurality of pipes of different lengths extending from said abutment into said outlet tubular member

for mixing air with the vaporized gasoline and any unvaporized gasoline from said vaporizing chamber, said abutment being formed with a passageway for each of said pipes, said passageways having respectively one end in free communication with said pipes and one end open to said auxiliary air inlet. 5

2. In a carburetor, means forming a T-shaped structure with one leg acting as an outlet, a second leg as an auxiliary air inlet, and the third leg as a vaporizing chamber, a wall arranged between said second and third legs in alignment with the first mentioned leg but spaced therefrom so that the second and third legs are in continuous communication with the lower end of the first mentioned leg, a plurality of pipes of different lengths extending from said wall into said first mentioned leg, said wall having a passageway for each of said pipes, said passageways opening into said auxiliary air inlet, a float 20 chamber adapted to receive gasoline, a plurality of tubes extending from said float chamber into said vaporizing chamber, and means for directing air across the upper end of each of said tubes, said means directing the air toward said vaporizing chamber, and means for regulating the air directed across said tubes. 25

3. In a carburetor, means forming a vaporizing chamber, means forming an auxiliary air inlet chamber, a tubular outlet member appreciably 30 longer than said vaporizing chamber, said outlet member having substantially equal sized openings registering with the vaporizing chamber and the air inlet member, tubes of different lengths extending into said outlet member centrally and 35 longitudinally thereof, one end of each of said tubes opening into said air inlet chamber whereby air is supplied to said outlet member at its inlet end and at spaced points along its length, means for supplying gasoline to said vaporizing 40 chamber, and means for directing air under pressure into said vaporizing chamber. 45

4. In a carburetor, tubular means formed with a tubular outlet member substantially centrally thereof, said outlet member extending substantially at right angle to said tubular means, a division member positioned substantially centrally of said tubular means, said division member extending to near said outlet member for dividing said tubular means into an air inlet chamber and a vaporizing chamber, both of said chambers discharging into said outlet member above said division member, a valve in said air inlet chamber for controlling the air passing therethrough, a plurality of tubes extending into said vaporizing chamber for directing carburetable fuel into said vaporizing chamber, and means at the end of said vaporizing chamber opposite said division member for directing air under pressure across the tops of said tubes for drawing fuel into said 60 vaporizing chamber. 55
